FURNACE

Ervin G. Bailey, Easton, Pa., assignor to Fuller
Lehigh Company, Fullerton, Pa., a corporation
of Delaware

Application March 17, 1928, Serial No. 262,363
Renewed October 7, 1932

22 Claims. (Cl. 122—235)

This invention relates to an improvement in the construction and operation of a furnace, and more particularly the type of furnace in which a slag-forming fuel is burned. With fuel such as 5 pulverized coal, which in burning forms slag, trouble has been experienced in disposing of the slag which is deposited in the bottom of the furnace directly from the burning fuel, or else gathers on the walls of the furnace and runs 10 down onto the floor.

The accumulation of slag on the floor is added to by chunks of slag which may collect in the furnace above the floor and then drop down when 15 they become loosened from the tubes. The slag on the floor, when it becomes cool, forms a solid mass of extremely refractory material which is difficult to remove, and it is to the removal of such slag that my invention is directed.

In the accompanying drawings, in which I have 20 shown a selected embodiment of the invention:—

Fig. 1 is a vertical sectional view through the lower part of a furnace, constructed according to 25 my invention.

Fig. 2 is a fragmentary section taken on the line 2—2 of Fig. 1.

Fig. 3 is a fragmentary elevation on an enlarged scale, and showing the interior of the furnace wall at the slag tapping opening.

Fig. 4 is a sectional view through the slag tapping opening, being taken on the lines 4—4 of Figs. 2 and 3.

Fig. 5 is a fragmentary elevation of the outer face of the furnace wall at the slag tapping and access openings, and taken on the line 5—5 of 35 Fig. 2.

Fig. 6 is a section on the line 6—6 of Fig. 4.

Fig. 7 is a sectional elevation illustrating the furnace shown in Figs. 1—6 as incorporated in a steam generator or boiler.

For the purposes of illustration, I have shown 40 my invention as applied to a furnace having substantially vertical walls, of which are shown three, 1, 2 and 3, each of which is formed by vertically extending water tubes 4, 5 and 6, respectively, connected at their lower ends to headers 7, 8 and 9 to which an appropriate covering may be applied. The upper ends of the water tubes are connected to the usual upper headers (see Fig. 7). Normally water is admitted to the 45 lower header rising through the tubes in the wall where some steam will be formed. Steam and water are discharged from the upper header. Such furnace walls would normally form part of a steam boiler and as such are termed water 50 walls.

It will be noted that each of the lower headers 55 is independent of the others, whereby each wall may expand and contract in a vertical direction independently of the others, and the lower headers are preferably carried on spring sup-

ports 10. The covering for the wall tubes may comprise individual tile or blocks 11, which are best shown in Figs. 4 and 6, these blocks being formed with refractory faces 12 and metallic backings 13 which are in close engagement with 5 the tubes, where they are held by suitable clamps 14. The details of the blocks and clamping means have been omitted from Fig. 2, for the sake of clearness, and because of the small scale of this figure.

The floor of the furnace is supported upon suitable beams 15 and sometimes comprises a single course of brick 16, although in the illustrated embodiment two courses are shown. Upon this course is preferably placed a layer of dolomite 15 17, and the course of brick is preferably laid loosely on the supporting plates 18 disposed on the beams 15.

Adjacent the edges of the floor, the plates 18 upon which the brick work is supported, extend 20 substantially into contact with the side walls, as best shown in Fig. 4. The brick work course 16 is provided with expansion joints 19, which are covered by a plurality of courses 20 extending along the walls.

In one or more of the side walls is disposed a 25 burner indicated generally at 21, and which is preferably adapted to burn pulverized coal. The burner should preferably be one which will give great turbulence to the incoming fuel, and it will 30 be noted that the burner is so arranged as to project a flame horizontally and relatively close to the floor.

In the embodiment shown, I contemplate placing a burner in each wall substantially in the position shown, so that the flames therefrom will intersect within the furnace and in such a way as 35 to cause still greater turbulence than is present in the individual streams of fuel, thus providing thorough mixture of the air and fuel, and complete combustion of the fuel.

The burning fuel will form slag, as is well known 40 in the art, and the major part of this slag will find its way to the floor of the furnace. Instead of 45 making efforts to cool the slag and cause it to form a relatively fine ash, as has been done in the past, I prefer to accumulate slag on the floor in the form of a quiescent pool of molten slag, and to tap this slag at will.

The slag is kept in its molten state by the proximity 50 of the streams of burning fuel which, as noted above, are relatively close to the floor, and therefore maintain the temperature of the slag on the floor sufficiently high, to keep it in its molten state.

The slag is preferably tapped through a suitable opening in one of the fluid cooled walls indicated at 22, from which it runs down a spout 23 associated with the opening 22. This spout is 55 preferably formed of two sections, as best shown 60

in Fig. 4, one section being supported between ears 24 and the other being pivoted at 25 upon these ears 24, and being provided with an apron 26 which, when the outer section 23' is lifted, will 5 close the end of the inner section of the spout.

Tapping of slag is intermittent, and between tapping periods the level of the slag pool rises, thereby completely submerging the floor and whatever may be upon it. By the rising and falling 10 of the slag level the contents may be thoroughly mixed in a molten condition through a process of liquid diffusion.

The tapped slag may be permitted to run into a sluiceway, where it may be subjected to jets of 15 water which will break it up and carry it away, or it may be tapped directly into a stream of running water. Again, it may be run on to the floor and quenched, or may be handled in any other suitable way. The slag at the opening 22 forms 20 a crust of chilled slag which may be easily broken by a bar, in order to permit the flow of slag, and then the slag may be permitted to run until the crust forms again and there is insufficient pressure behind it to break it, or if desired, the hole 25 may be plugged, to stop the flow of slag before the crust would form by itself. In this connection, it should be noted that the spout forms a convenient guide and rest for a bar used in working at the tap hole.

30 Adjacent the tap hole, I preferably provide an access door indicated at 27. Normally, this door is bricked up as shown in Figs. 1 and 2, the brick being removed when it is desired to enter the furnace through the door.

35 Disposed in front of the two openings formed by the door and the tap hole, and spaced from the wall of the furnace, is a transversely extending header box 28. This box preferably extends beyond both openings and is connected to the wall 40 tubes above these openings, these tubes being bent outwardly as best shown in Fig. 4, and expanded into the box.

Disposed beneath the door 27 is a second transversely extending header box 29, connected by 45 nipples 30 to the header 8. The boxes 28 and 29 are connected by nipples 31 disposed on opposite sides of the door 27. Disposed on opposite sides of the tap hole are two nipples 32, which connect the header 8 to the box 28.

50 By the above arrangement, a convenient disposition of the access door is provided, and proper circulation of water past both the access door and tap hole is also obtained. At the same time, the tubes are disposed far enough from the tap hole to prevent their chilling the slag and thus preventing or hindering its flow.

Air may be introduced beneath the floor through the conduit 33, to aid in maintaining the floor and the supporting steel work relatively cool.

60 In operation, the furnace is started and as the slag accumulates on the floor, it is maintained in a molten condition by the intense heat of the fire which is relatively close to the floor. It will be noted that the dolomite covering forming part of 65 the floor is extended upwardly toward the walls, as best shown in Fig. 1, this material being installed loose.

As the slag accumulates and reaches a point above the tap hole, it may be tapped off if found 70 desirable. If it is intended to use the slag for manufacturing purposes, as an ingredient in a composition of matter for which it may be suitable, any desirable material may be added to the pool of slag before tapping. For example, limestone or feldspar are substances which may be 75

added, although of course I do not intend to limit myself to those substances alone. Such material may be introduced through the usual observation doors, not shown.

As the molten slag accumulates, a pressure is exerted laterally against the walls of the furnace, and this pressure may be taken up by the sliding expansion joint between the floor and the walls. Similarly, the heat from the burning fuel may cause expansion of the walls, and this action may 10 take place against the opposition of the resilient supports 10. It will be observed that the spout 23 is adapted to move with the wall upon expansion or contraction of the wall, as just described.

The heat from the pool of molten slag will aid 15 materially in maintaining a high furnace temperature, and the heat is partly carried to the wall tubes by means of the heat conducting tile supported on the tubes, the tubes maintaining the walls cool, so that the high temperature generated 20 by the burning fuel and the pool of slag does not destroy them. The walls are preferably made of the heat conducting tile indicated in Fig. 4, except at the two openings where a magnesite or other suitable brick may be employed instead of 25 the tile. Such brick are easily replaceable when burned out. By this means, a high furnace temperature may be maintained without damage to the walls, the heat passing through the tile which are of high conductivity, and thence into the 30 water or other medium circulating in the tubes in the walls. Thus, the walls are not only maintained in the presence of a high furnace temperature, but the heat is put to a useful purpose. At the same time, ample provision is made for expansion and contraction of the walls.

It will be noted that the refractory and metal parts of the furnace bottom are arranged to insure that there will be no "leaks" of slag there-through. By a "leak", I mean a slag flow at a 40 place other than that at which the slag is intentionally permitted to flow from the furnace, at which place, of course, proper provision will be made against damage from such flow. If such a leak were permitted, the stream of liquid slag 45 flowing through such a leak, would soon "cut" the refractory and even the metal parts, by dissolving and eroding the materials along which the slag flows. This is not true, however, of casual openings extending only partially through the 50 floor. The heat from the slag which would flow into such openings may be conducted away with the floor cooling provisions described fast enough to cause such slag to solidify in the openings. In other words, a continuous flow of slag will "cut", 55 whereas quiescent slag has little or no effect in this respect.

Similarly, the flow of fluid slag down the side walls of the furnace would soon "cut" these walls, were it not for the cooling of these walls by the 60 tubes, which keeps the wall surfaces below the temperature necessary to cause the materials thereof to enter into solution in the slag. This is aided by any layer of solidified or semi-solidified slag which may adhere to such surfaces.

In the construction described, the slag from the side walls flows out on the furnace floor, where it joins the slag deposited directly on the floor from the combustion space to form a fluid mass. The joint between the sides of the floor and the side walls is kept tight enough to insure that the slag will not leak through at this point. The angle iron connected to the lower part of each wall, on which plate 18 rests, forming an effective seal for this purpose. By carrying the water 70 75 75

tubes well below the top of the floor, protection of all parts of the wall which may be contacted with fluid slag is insured.

The maintenance of the furnace floor in a relatively cool condition by supplying cooling air in contact therewith cools the lower layer of slag on the floor and renders that portion of the slag less fluid than the upper portion of the collected slag. The cooler layer of slag in contact with the refractory portion of the floor tends to minimize dissolving of the refractory by the slag and erosion of the refractory when slag is withdrawn through the tap hole.

It will also be understood that the furnace may be operated at times under conditions in which collected slag on the floor will not be fluid. Thus, when the furnace is used in connection with a boiler, there may be lay-over periods during which the combustion rate may be so low that there will not be a sufficiently high furnace temperature to maintain the slag on the floor molten. As soon as the combustion rate is increased, however, to put the boiler into full operation, the increased temperature of the furnace will first put the upper part of the accumulated slag into a condition in which it may flow from the furnace. Therefore, when I describe the slag as being maintained in a molten condition, I do not intend that it must be in such condition at all times, but only at such times as the furnace is in normal operation.

Moreover, it is to be understood that, even when the slag is flowing through the tap hole 22 or other outlet opening, there is a pool of slag maintained, even if such opening is never closed, because the molten slag flowing over the floor will keep a layer of molten slag on the floor to prevent any hardened layer on the top of the floor from melting, which would permit the floor to be "cut" by the flowing slag. Where the slag is tapped intermittently, as in my preferred form, this protection is insured by locating the bottom of the tap hole in the side wall above the top of the floor.

45 I claim:

1. In a furnace, means for burning a slag-forming fuel, vertical walls comprising a plurality of tubes and heat-conducting tile in contact therewith, a floor upon which the slag may accumulate in a molten condition, means permitting relative movement between the floor and the walls, and means resiliently supporting the walls.

2. In a furnace, a combustion chamber, a burner to burn a slag-forming fuel in said chamber, said chamber having a substantially horizontal slag receiving floor and side walls held in contact with the sides of the floor and arranged to prevent slag leaking therebetween, and vertical water tubes in said side walls and extending below the top of said floor, the faces of said side walls being formed of heat conducting blocks attached to and in close thermal contact with said tubes, some of said blocks contacting with the sides of said floor, said chamber having an opening through which molten slag may flow and said burner being constructed to impart sufficient heat to slag on said floor to maintain at least its surface in a fluid condition.

70 3. In a furnace, a combustion chamber, a burner to burn a slag-forming fuel in said chamber, said chamber having a substantially horizontal slag receiving floor and side walls held in contact with the sides of the floor and arranged to prevent slag leaking therebetween, and vertical

water tubes in said side walls and extending below the top of said floor, said chamber having an opening through which molten slag may flow and said burner being constructed to impart sufficient heat to slag on said floor to maintain at least its surface in a fluid condition, said floor having a relatively thick layer of ceramic material and a metal supporting plate therefor.

5 4. In a furnace, a combustion chamber, a burner to burn a slag-forming fuel in said chamber, said chamber having a substantially horizontal slag receiving floor and side walls held in contact with the sides of the floor and arranged to prevent slag leaking therebetween, and vertical water tubes in said side walls and extending below the top of said floor, said chamber having an opening through which molten slag may flow and said burner being constructed to impart sufficient heat to slag on said floor to maintain at least its surface in a fluid condition, said floor having a relatively thick layer of ceramic material and a metal supporting plate therefor, said floor having a space beneath said plate, whereby heat therefrom may be conducted slowly away.

10 5. In a furnace, means for burning a slag-forming fuel, a floor constructed to support a pool of molten slag, water cooled walls contacting with the edges of said floor, and means permitting relative horizontal and vertical movement between said walls and said floor, in combination with a 15 spout coating with a slag tap opening in one of said walls above the level of said floor and movable therewith upon movement of said wall.

20 6. In a furnace, means for burning a slag-forming fuel, a floor constructed to support a pool of molten slag, water cooled walls surrounding said floor, and resilient means supporting said walls independently of said floor, in combination with a spout associated with an opening in one 25 of said walls and adapted to move therewith upon movement of the wall.

25 7. In a furnace, means for burning a slag-forming fuel, water cooled walls, and a floor having a refractory covering, said floor being constructed to support a pool of molten slag, in combination with means for sealing the joint between the water cooled walls and floor.

30 8. In a boiler furnace, means for burning a slag-forming fuel, water cooled walls, and a floor constructed to support a pool of molten slag, said floor having a support independent of the walls and movable relatively thereto, in combination with means forming a seal between said walls and said floor, said means preventing passage of slag between said floor and said walls upon relative movement between said walls and said floor, substantially as described.

35 9. In a furnace, means for burning a slag-forming fuel, a floor constructed to support a pool of molten slag, water cooled walls surrounding said floor, and resilient means supporting said walls independently of said floor, in combination with a spout associated with an opening above the floor in one of said walls and adapted to move therewith upon expansion or contraction of the wall, said walls being constructed and arranged so that slag may drain from said walls to said floor.

40 10. In combination, a furnace, water circulating tubes in the walls thereof, means for burning fuel in said furnace, means for maintaining a pool of molten material within the furnace, means for applying the heat from the burning fuel and from the molten pool to the water circulating tubes in the walls, and means for introducing an 45

independent cooling fluid beneath the floor of said furnace to aid in cooling the same.

11. A furnace comprising walls and a floor, water cooling means for the walls only, said floor being constructed to support a pool of molten slag, and means for projecting a slag-forming fuel substantially horizontally close to the floor.

12. A furnace comprising walls and a floor, water cooling means for the walls only, said floor being constructed to support a pool of molten slag, and a turbulent burner of high capacity arranged to project a slag-forming fuel substantially horizontally close to the floor.

13. In a furnace, a combustion chamber, a burner to burn a slag-forming fuel in said chamber, said chamber having a substantially horizontal slag receiving floor and side walls held in contact with the sides of the floor and arranged to prevent slag leakage therebetween, and vertical water tubes in said side walls extending below the top of said floor, said chamber having an opening through which molten slag may flow, and said burner being constructed to impart sufficient heat to slag on said floor to maintain at least its surface in fluid condition, said floor having a relatively thick layer of refractory material and a metal supporting plate therefor, said floor also having space beneath said plate whereby heat therefrom may be conducted away.

14. A boiler furnace, a floor therefor having metal supporting parts and a solid protective layer arranged to support a pool of molten slag, means for fluid cooling said metal floor parts, means for feeding finely-divided slag-forming fuel and air into the furnace and arranged to maintain a pool of molten slag overlying substantially all the solid protective layer, said furnace having a slag tap-hole, side walls adjacent to the slag pool, all of said side walls having metal conduits, and connections for circulating cooling liquid through said metal conduits.

15. A boiler furnace, a floor therefor having metal supporting parts, blocks carried by the metal supporting parts and forming a solid protective layer arranged to support a pool of molten slag, means for fluid cooling said metal floor parts, means for feeding finely-divided slag-forming fuel and air into the furnace and arranged to maintain a pool of molten slag overlying substantially all the solid protective layer, said furnace having a slag tap-hole, side walls adjacent to the slag pool, all of said side walls having metal conduits, and connections for circulating cooling liquid through said metal conduits.

16. A boiler furnace, a floor therefor having metal supporting parts and a solid protective layer arranged to support a pool of molten slag, means for fluid cooling said metal floor parts, means for feeding finely-divided slag-forming fuel and air into the furnace and arranged to maintain a pool of molten slag overlying substantially all the solid protective layer, said furnace having a slag tap-hole, side walls adjacent to the slag pool, all of said side walls having metal conduits forming spaced water tubes in said side walls and closure means for closing the spaces between said tubes and in thermal contact therewith, and connections for circulating cooling fluid through said metal conduits.

17. A boiler furnace, a floor therefor having metal supporting parts and a solid protective layer arranged to support a pool of molten slag, means for fluid cooling said metal floor parts, means for feeding finely-divided slag-forming fuel and air

into the furnace and arranged to maintain a pool of molten slag overlying substantially all the solid protective layer, said furnace having a slag tap-hole, side walls adjacent to the slag pool, all of said side walls having metal conduits forming spaced water tubes in said side walls and closure means for closing the spaces between said tubes, said closure means having metallic parts in thermal contact with said tubes and refractory on said metallic parts, and connections for circulating cooling liquid through said metal conduits.

18. A boiler furnace, a floor therefor having metal supporting parts and a solid protective layer arranged to support a pool of molten slag, means for fluid cooling said metal floor parts, means for feeding finely-divided slag-forming fuel and air into the furnace and arranged to maintain a pool of molten slag overlying substantially all the solid protective layer, said furnace having a slag tap-hole, side walls adjacent to the slag pool, all of said side walls having metal conduits forming spaced water tubes in said side walls and closure means for closing the spaces between said tubes and in thermal contact therewith, said water tubes being arranged for less cooling in some side wall areas than in others, and connections for circulating cooling liquid through said metal conduits.

19. In a pulverized fuel fired furnace, the combination of a combustion chamber having a bottom and side walls adjacent to a slag pool on said bottom, all of said side walls having fluid cooling tubes and a lining for said tubes constructed and arranged to retain a pool of molten slag overlying substantially all of said combustion chamber bottom, and means for feeding pulverized fuel and air into said chamber arranged to produce slag liquefying temperature in said slag pool.

20. A boiler furnace, a floor therefor having metal supporting parts and a solid protective layer arranged to support a pool of molten slag, means for fluid cooling said metal floor parts, said furnace having a slag tap-hole, side walls adjacent to the slag pool, all of said side walls having metal conduits, a burner between certain of the metal conduits and arranged to maintain a pool of molten slag overlying the solid protective layer of the floor, and connections for circulating cooling liquid through said metal conduits.

21. A boiler furnace, a floor therefor having metal supporting parts and a solid protective layer arranged to support a pool of molten slag, means for fluid cooling said metal floor parts, said furnace having a slag tap-hole, side walls adjacent to the slag pool, all of said side walls having metal conduits located above the furnace bottom, a burner between certain of the metal conduits and arranged to maintain a pool of molten slag overlying the solid protective layer of the floor, and connections for circulating cooling liquid through said metal conduits.

22. In a steam generator, a furnace having a pulverized fuel burner, a bottom, side walls and an upper gas outlet, a steam generating tube bank arranged to receive heating gases from said outlet, said side walls being arranged to form an enclosure for a pool of molten slag overlying substantially all of said furnace bottom, said side walls including means for fluid cooling all boundary portions of the enclosure, and said pulverized fuel burner being arranged to maintain the slag in said slag pool in a molten condition.
